UNITED STATES PATENT OFFICE

WILLIAM P. FROST, OF JACKSON HEIGHTS, NEW YORK, ASSIGNOR TO EVANS ELEVATOR EQUALIZER COMPANY, OF BEDFORD, INDIANA, A CORPORATION OF INDIANA

DEVICE FOR EQUALIZING STRAIN ON HOISTING ROPES

Application filed January 27, 1932. Serial No. 589,144.

My present invention relates to a device for equalizing the strain upon a group of hoisting ropes or other tension members connected to a common load, as an elevator car, or 5 the counterweight of such a car. In my pending application for patent, filed January 10, 1931, Serial No. 507,967, I have illustrated and described a novel equalizing device for the purpose mentioned in which pairs of up- 10 per floating pulleys connected to the hoisting ropes and pairs of lower pulleys pivoted to the car are employed and in which two strands of equalizing cable engaging said pulleys are employed as the connecting and 15 equalizing rigging. My present invention is in some respects a modification of the construction covered by said application and among its objects are the provision of improvements in the construction of the pull 20 bars connected to the hoisting ropes and the safety frame through which the pull bars extend, improvements in the construction of the bearing members in which the lower pulleys are mounted, and improvements in the 25 arrangement of the rigging by which the tension upon the two strands of the equalizing cable is equalized. In the appended claims I have more particularly pointed out the essential elements of my invention and 30 distinguished it from the prior art so far as known to me.

In the drawings Figure 1 is what may be termed a side view of my novel equalizing 35 device;

Fig. 2 is a transverse vertical section of the device near one end thereof, the plane of the section being indicated by the dotted line 2-2 of Fig. 1;

Fig. 3 is a horizontal section on the line 3-3 of Fig. 1;

Fig. 4 is a bottom plan view of the device;

Fig. 5 is a vertical transverse section in a 45 plane indicated by the dotted line 5-5 of Fig. 1;

Fig. 6 is a perspective of one of the pull bars 15, detached;

Fig. 7 is a fragmental vertical section 50 showing the construction of the connection

between one of the shackle bolts secured to the hoisting ropes and its associated pull bar;

Fig. 8 is a perspective of one end of a channel plate forming part of the framework of the device, and

Fig. 9 is a diagrammatic view showing the tracking of the equalizing cable between the upper and lower pulleys.

Like reference characters indicate like parts on all the figures of the drawings.

In the present instance my device is designed to be used in connection with a group of six hoisting ropes A, the ends only of which are shown, it being understood that the ropes travel around a suspension or hoisting pulley and are connected at their opposite ends to a counterweight, as usual in elevator installations. By means of my novel equalizing device the hoisting ropes are connected to the cross-head members B of the car, fragments only of which are shown, the car being assumed to be of the usual construction employing as such cross-head members structural iron beams which are of channel shape in cross-section.

The bearings by means of which the lower pairs of twin pulleys or contiguous parallel lower pulleys are pivotally connected to the car are formed in bearing lugs extending downwardly from a bearing plate 1 which is disposed within the depending front and rear flanges of a channel plate 2 supported by a pair of lower cross-bars 3-3 of angle iron which extend under the bottom flanges of the cross-head members B of the car above referred to. To provide for connecting the channel plate 2 to the cross bars 3 the flanges of the former are cut away for a short distance at opposite ends of the plate and the cross bars are orificed to receive the ends 2a

of the cross portion of the plate projecting beyond the line of the cuts. Clamping bolts 5 engaging the cross bars 3 and upper cross bars 6 serve to clamp the cross bars and through them the entire equalizing device to the cross-head members B of the car frame.

The bearing plate 1 is formed with a pair of bolt holes at each end arranged to receive frame bolts 7, arranged to support a com-

posite guide and safety frame which may be next described.

This safety frame consists of two outer frame plates 8 and 9 and an inner frame plate 10 which are arranged horizontally and edgewise parallel with each other, and which are spaced apart by a pair of trunnion blocks 11 at each end of the plates. The trunnions of the blocks project into orifices 10 in the plates formed to receive them and the plates are secured together by screws which serve as guides for separating and guiding the pull bars later to be described. These connecting screws have heads engaging the outer plates 8 and 9 and threaded end engaging seats in the inner plate 10, and are arranged in staggered relation on opposite sides of said inner plate to accommodate the staggered arrangement of the pull bars.

20 The trunnion blocks are orificed vertically to receive the bolts 7, and a pair of orificed bearing plates 12, one at each end of the frame plates, are arranged above said plates and the trunnion blocks at opposite ends of 25 the plates. A spacing sleeve 13 surrounds each bolt 7 between the bearing plate and the several trunnions, and the guide frame is clamped down upon these spacing sleeves by nuts engaging the threaded ends of the bolts.

30 The hoisting ropes A of the elevator apparatus are individually connected each to a pair of contiguous parallel upper floating pulleys which by means of an equalizing cable are connected to the lower pulleys secured in the manner already described to the car. Each such rope is secured to a rope socket forming part of a shackle bolt 14 which is adjustably secured to the upper end of a pull bar 15 loosely passing through one 35 of the spaces between the frame plates and connecting screws of the guide frame.

The pull bars, as shown, consist each of two parallel side portions 16—16 connected at the top by a cross-head portion 17 orificed 45 to provide for connection with the associated shackle bolt. This connection (see Fig. 7) consists of a tubular connecting block 50 formed with a shouldered head 51 at the lower end to engage the orifice in the cross portion 17 of the pull bar, and a threaded section above the plane of the top of the pull bar to receive a lock nut 52. Above the plane of the lock nut the block is formed with a polygonal face through which it may be held 55 by a suitable tool from turning during adjustment of the connection. The bore of the block is threaded to receive the lower threaded end of the shackle bolt, a lock nut being employed above the connecting block to 60 secure it against disengagement.

The lower ends of the side portions of the pull bar are also formed with a connecting cross portion 18 which is formed with a pair of bearing lugs 19—19 between which are pivoted one pair of the upper floating pul-

leys above referred to. The pulleys of each pair are in the present instance, though not necessarily, of identical construction and are independently rotatable on a common axis. It will be noted that the pairs of pulleys are 70 arranged in two rows of three pairs each, the pulleys of each row being parallel and the pairs being arranged in staggered relation. For convenience of description, the twelve upper pulleys are severally marked 20 to 31 75 reading from left to right as viewed in Fig. 3.

The twelve lower pulleys (severally marked 32 to 43) are likewise arranged in pairs, and are so arranged angularly with 80 relation to the upper pulleys that loops of the equalizing cable 44 engaging the lower pulleys will track upwardly to different upper pulleys above them. The equalizing cable is provided with sockets 45 and 46a 85 at its opposite ends, and from its anchorage at socket 45 the cable in turn engages upper and lower pulleys 30, 40, 26, alternately in a generally zig-zag path until it passes below the two right hand lower pulleys 42 and 43 90 which are single pulleys individually mounted in line with each other, whence it passes to pulley 31 and thence in a path adjacent that before described around pulleys parallel to those engaged in its first circuit to 95 its anchorage 46a beneath the upper pulley 28. It will be noted that the pulleys 42 and 43 provide means adjacent the center of the length of the equalizing cable for equalizing the strain and accommodating any stretch 100 which may occur and will function the same at all times regardless of the amount of stretch on either side of the pulleys.

I claim:

1. An equalizing device for connecting an 105 elevator car to a group of hoisting ropes comprising a plurality of pairs of contiguous parallel floating upper pulleys connected one pair to each of said ropes, a plurality of pairs of contiguous parallel other lower pulleys pivotally connected to the car, one or more single pulleys lying in one plane individually pivoted to the car, and an equalizing cable anchored to the car at its ends and engaging from its point of anchorage at 110 each end one member of each of said pairs of upper pulleys and pairs of lower pulleys in alternation and adjacent the center point of its length engaging said individually mounted pulleys.

2. An equalizing device for connecting an 115 elevator car to a group of hoisting ropes comprising a plurality of pairs of contiguous parallel floating upper pulleys connected one pair to each of said ropes, a plurality 120 of pairs of contiguous parallel other lower pulleys pivotally connected to the car, two single pulleys individually pivoted to the car in a common plane, and an equalizing cable anchored to the car at its ends and en- 125

130

- gaging from its point of anchorage at each end one member of each of said pairs of upper pulleys and pairs of lower pulleys in alternation and adjacent the center point 5 of its length engaging said two single pulleys and tracking from one such pulley to one member of a pair of upper pulleys and tracking from the other such pulley to one member of another pair of upper pulleys.
- 10 3. An equalizing device according to claim 1 in which the half of the equalizing cable leading from one end anchorage to the central individually mounted pulleys, and the half of the cable leading from said central 15 pulleys to the other end anchorage track in the same order in adjacent zig-zag paths between the upper and lower pairs of pulleys.
4. In a supporting frame assembly for an equalizing device arranged to be secured 20 to a pair of spaced cross-head members of an elevator car, a pair of orificed cross-bars extending under and secured to said cross-head members a channel-iron plate having its side flanges cut away to provide projecting 25 ends extending from the body of the plate, said ends extending through the orifices of said cross-bars, and a bearing plate seated within the flanges of said channel-iron plate and secured thereto formed with bearings.
- 30 5. A supporting frame and guide plate assembly for an equalizing device arranged to be secured to a pair of spaced cross-head members of an elevator car comprising a pair of orificed cross-bars extending under and 35 secured to said cross-head members, an orificed channel-iron plate having its side flanges cut away to provide projecting ends extending from the body of the plate, said ends extending through the orifices of said 40 lower cross-bars, an orificed bearing plate seated within the flanges of said channel-iron plate formed with bearings, frame bolts engaging the orifices of said channel-iron plate and bearing plate and arranged to secure 45 said plates together, and a guide frame secured to said bolts.
6. A supporting frame and guide frame assembly for an equalizing device arranged to be secured to a pair of spaced cross-head 50
- members of an elevator car comprising orificed lower cross-bars extending (and secured) under said cross-head members, upper cross-bars above said cross-head members, clamping bolts connecting said lower and upper cross-bars, an orificed channel-iron plate having its side flanges cut away to provide projecting ends extending from the body of the plate, said ends extending 70 through the orifices of said lower cross-bars, an orificed bearing plate seated within the flanges of said channel-iron plate formed with depending bearing lugs, frame bolts engaging the orifices of said channel-iron plate and bearing plate and arranged to 75 clamp said plates together, and a guide frame secured to said bolts.
7. In an equalizing device of the character described and including hoisting ropes and floating pulleys and equalizing rigging, means for connecting the hoisting ropes individually to the floating pulleys including a pull bar formed with an upper cross-portion arranged to be secured to the associated rope, opposite parallel side portions, and a lower cross-portion formed with depending lugs provided with bearings for the associated pulley.
8. In an equalizing device of the character described and including hoisting ropes and floating pulleys and equalizing rigging, means for connecting the hoisting ropes individually to the floating pulleys including a pull bar formed with an orificed upper cross portion, side portions and bearing portions at the bottom of said side portions, said upper cross-portion being equipped with a tubular interiorly threaded connecting block formed with a lower shouldered head and an exteriorly threaded section provided with a lock nut above said cross-portion of the pull bar and a polygonal section above said threaded section, and a shackle bolt arranged to engage the threaded bore of said connecting block, said shackle bolt being connected to the associated rope.

In testimony whereof, I have subscribed my name.

WILLIAM P. FROST.
